[57] CLAIM

The ornamental design for luggage container vehicle
accessory, as shown and described.

DESCRIPTION

FIG. 1 is a top, left, rear perspective view of a luggage
container vehicle accessory showing my new design;
FIG. 2 is a left side elevational view, the right side being
a mirror image;

FIG. 3 is a front elevational view; and

FIG. 4 is a bottom plan view.

The broken line showing of the trunk portion of a car in
FIG. 1 is for illustrative purposes only and forms no
part of the claimed design.
